INFLATABLE BOAT

Cresson H. Kearny, United States Army

Application October 24, 1941, Serial No. 416,329

15 Claims. (Cl. 9—2)

(Granted under the act of March 3, 1883, as
amended April 30, 1928; 370 O. G. 757)

This invention described herein may be manufactured and used by or for the Government for governmental purposes, without the payment to me of any royalty thereon.

This invention relates to an inflatable boat of the type which can be transported easily and prepared for use without undue delay. More particularly, it refers to an inflatable boat which can be inflated quickly by a low pressure means such as the human breath and which utilizes trapped water as a stabilizing means. Because of its light weight and rapid assembly, my boat is especially adapted for military use but is equally serviceable to hunters, fishermen, explorers, pleasure-seekers, or, in short, to any one desiring a small pneumatic water transport.

It is well known to use pneumatic members for obtaining extreme buoyancy in water craft and to provide these pneumatic members with strengthening attachments and with load supporting attachments. It is also well known to stabilize inflatable floating apparatus by means of ballast weights. By my invention, I provide a small pneumatic boat which is extremely rigid without the necessity of using auxiliary bracing for the pneumatic members and which is extremely stable without the necessity of using special ballast weights. Moreover, I do not sacrifice lightness, portability, or ease of assembly to attain these advantages.

It is, accordingly, an object of the present invention to provide an inflatable boat which contains a plurality of wide-aperture, low-pressure valves whereby the boat can be readily inflated by means of the human breath.

Another object is to provide an inflatable boat which is stabilized by water trapped in the bottom portion of the boat as well as by a partial vacuum action in a space above the trapped water on the up-tilted side of the boat.

Another object is to provide an inflatable boat in which stress concentrations are distributed because of the multi-compartment design and in which the tendency to buckle is lessened because water pressure is exerted against the wall surrounding the opening in a substantially doughnut-shape buoyant member and directly against the load container as well as against the outside wall of the buoyant member.

Other objects and advantages of my invention will become apparent from the following detailed description and the attached drawing and the invention will be pointed out with particularity in the appended claims.

In the drawing:

Fig. 1 is a plan view of my boat with the boat bottom and inner-sheet removed;

Fig. 2 is a sectional view on lines 2—2 of Fig. 1 with the boat bottom and inner-sheet shown;

Fig. 3 is a plan view of the boat bottom; and

Fig. 4 is a sectional view, along the longitudinal axis, of a wide-aperture, low-pressure valve which I use in my boat.

Referring to Fig. 1, 1 indicates the housing for the pneumatic members which is approximately toroidal or doughnut-shaped and which is formed from a plurality of compartments or segments 2, seven such segments being provided in the embodiment shown. The walls of the housing 1 may be made of ordinary tight woven shirt cloth, or any such suitable material. The individual air compartments or segments 2 are sewed together and provided with cloth partitions 3 sewed to the inner side of the seam line between the compartments 2. With the partitions 3 in position, seven individual air compartments 2 are formed which have a teardrop cross-section, as illustrated in Fig. 2. Each air compartment 2 contains a bladder 4 in the form of a rubber balloon, preferably of the type ordinarily used by the Signal Corps of the United States Army, although other materials may be used for constructing the bladder as long as the material used is deformable and has properties insuring a high resistance to the deteriorating action of salt water. By means of valves 5, these individual balloon-bladders 4 may be inflated or deflated, and when inflated conform closely to the shape of the air compartment 2.

Valves 5 are illustrated in detail in Fig. 4. As shown there, each valve is made up of a body member 6, a plug member 7, a valve stem 8, and a plurality of resilient bands 9 and 10 for holding the various component parts in assembled relation. Body member 6 is a hollow tubular member, flared at the bottom, and may be made of glass. An ordinary glass bottleneck will serve satisfactorily. Plug 7 bears against the sloping interior wall of member 6 to effectively prevent the escape of air from bladder 4. I construct plug 7 by filling a bulb of doubled toy balloon rubber with a low freezing point liquid 11 such as glycerine. A valve stem 8 extends into the interior of valve plug 7 and projects above the mouth of member 6. Resilient bands 9, such as ordinary thin rubber bands, extend around opposite ends of plug 7 to seal the liquid 11 therein. Where stem 8 enters plug 7, bands 9 compress the rubber sides of the opening in plug 7 tightly against the valve stem. At this same location, bands 9 also secure one end of a plurality of thin rubber bands 10 which are

stretched from the interior of the valve, over the edge of the mouth of member 6 to beneath the bead 12 on member 6 where they are again secured by another set of bands 9.

Since the bands 10 are in tension, they exert a force on plug 7 tending to wedge it against the inside sloping wall of member 6. This force is sufficient to wedge plug 7 tightly enough to prevent the escape of air from bladder 4 but it can be overcome by the force of the human breath. Because the aperture in member 6 is comparatively wide, a person can empty his lungs into bladder 4 almost as fast as he can breathe. Similarly, bladder 4 can be deflated in a very few seconds merely by pressing down upon valve stem 8. The valves 5 are held in position for instant use by being attached with resilient members, such as ordinary rubber bands, to tabs 13 fixed to the walls of the air compartments 2.

The lift of the balloon-bladders 4 is transmitted to the load of the boat through a flange 14, which may be made of doubled heavy canvas, attached to the continuation of the teardrop cross-section ridge of the cloth compartments 2. Across the bottom of the cylindrical flange 14 is sewed a flat light-canvas bottom 15, shown more completely in Fig. 3. The canvas member 15 gives the boat a smooth bottom and acts to trap the water ballast as described more fully hereafter. Small strips of canvas are stitched to the upper side of the bottom member 15, thereby forming tubes 16 through which additional members 16', such as wooden rods, are run through holes 17 in the cylindrical flange 14 to give rigidity to the bottom member 15. The strengthening members 16' contained in the tubes 16 act as beams to transmit the downward pressure of the load carried by the boat to the cylindrical flange 14, and are tied in place by cords 18 which in turn are tied to the cylindrical flange 14. If desired, the boat may be used without placing strengthening members 16' in the tubes 16.

The load of the boat is carried dry in a bucket like depression made by placing a waterproof sheet 19, preferably waterproofed canvas, over the walls of the pneumatic member housing 1. This separate sheet 19 can be used as a tent-fly or as a shelter-half for a tent since it is not necessary to stitch it or otherwise attach it to the rest of the boat. Thus, it will be seen that the sheet 19 need not be of any special shape as long as it fits over the sides of the pneumatic housing 1, although if desired, a special canvas bucket could be provided for carrying the load which would work as satisfactorily as sheet 19 as long as it was waterproof.

When it is desired to use the boat, the individual bladders 4 are inflated causing the housing 1 to assume its generally toroidal or doughnut shape. Strengthening rods or sticks 16' may or may not be inserted into the tubes 16 depending upon the user's desire. Then the boat, less the load containing inner sheet 19, is placed into the water which begins to leak slowly through small openings or ports 20 in the bottom 15, and through those portions of openings 17 which are not blocked by the strengthening members 16' projecting from tubes 16, until the average water level in the interior of the boat is the same as the average outside water level. Meanwhile, the load containing inner sheet 19 is placed across the top of the boat where it rests upon the upper surface of the housing 1 to form a loose air seal. Sheet 19 is depressed in the center to form a space for the load. If desired, sheet 19 can be placed in position before the boat is put into the water.

When the boat, assembled and loaded, is floating in the water, the water which has leaked in through openings or ports 20 in the bottom 15, and through the unblocked portions, if any, of the openings 17 in flange 14, is confined in a space 21 bounded by the bottom 15, the interior side of the housing 1 for the pneumatic members, the side forming the opening in the doughnut shape, and the inner sheet 19. The amount of water confined in this space will depend upon the displacement or, in other words, upon the load contained in inner sheet 19. This trapped water acts as a stabilizing medium for the boat since it has an appreciable weight and inertia. The inertia of the trapped water adds to the inertia of the rest of the boat to oppose sudden movement in a horizontal direction. A change in a vertical direction, such as tilting, is resisted by the weight and inertia of the water on the uplifted side. This occurs because the openings 20 in bottom 15, and the unblocked portions, if any, of openings 17 in flange 14, are so small that the water can escape but slowly from space 21 on the upraised side and consequently the trapped water-ballast is lifted above the outside water level on the uptipped side where it acts as a weight to right the boat. An added stabilizing effect is obtained from atmospheric pressure exerted upon the uptilted side. When one side of the boat is raised, the water level in space 21 on that side drops, somewhat tending to create a partial vacuum above the water because passage of air through the space between pneumatic housing 1 and inner sheet 19 is restricted by the loose air seal produced by sheet 19. Because of this vacuum action the water in space 21, on the uptipped side, is raised above the outside water level even when the boat is without the canvas bottom 15. Since the sealing action of inner sheet 19 is not perfect, a partial vacuum in a portion of space 21 will not last indefinitely, but it does last long enough to produce an immediate added stabilizing effect. Similarly, the water trapped in the upraised portion of space 21 will leak out ultimately, but for a short interval it exerts a force, due to its weight and inertia, which tends to oppose a change in its position. The combined result of the vacuum action plus the water-ballast trapping and lifting by the canvas bottom 15 results in efficient stabilizing of the boat.

From the above description, it will be seen that I have invented a boat which is extremely simple to build, light in weight and easy to assemble, and one which is rigid and stable when in operation. The boat is constructed of materials which are easy to obtain and a certain amount of flexibility in the choice of materials is allowed. When the parts are assembled, they can be folded and packed into a small bundle which weighs less than ten pounds. This bundle can be fitted into a soldier's pack, where one component of the boat, the tent shelter half which can be used as the waterproof inner sheet 19, is normally carried. After the site of use is reached, the boat can be prepared for use quickly because of the easy inflating action of the valves in the individual bladders. Similarly, it can be quickly deflated and repacked after use. If it is desired to use strengthening members for the bottom 15, improvised means such as the branches of small trees in the vicinity, or any equally applicable locally-cut sticks can be used, as long as the means used will fit into the tubes 16.

Since water pressure is exerted against the interior side of the toroidally or doughnut-shaped pneumatic housing, the side adjacent to the interior of the boat, and against the bulk of the

load in the load containing inner sheet as well as against the exterior side of the pneumatic housing, there is less tendency for the boat to buckle in the center and internal cross-bracing can be dispensed with. The multicompartment design, using a plurality of individual bladders, insures a distribution of the lifting effort and minimizes the danger of sinking since the failure of an individual bladder does not remove the entire lifting effort. Should one of the bladders fail when the boat is in use, a spare bladder can be inserted without much difficulty. The toroidal, multicompartment design having a teardrop cross section with a strengthening flange and bottom attached thereto provides a structure strong in relation to its weight, one which greatly reduces stress concentrations at any particular point, and one which is capable of carrying at least two persons of average weight with safety. Furthermore, the addition of a simple waterproof sheet, which need not be attached or fastened to the rest of the boat, but instead is merely laid across the upper surface of the boat and depressed in the center, furnishes a comparatively dry load container and also completes a space for trapping water which results in an efficient stabilizing action without added weight as previously explained.

While I have described and illustrated a particular embodiment of my invention, it is to be understood that I do not wish to be restricted thereto, but intend to cover all modifications thereof which fall within the true spirit and scope of the appended claims.

Having described my invention, what I claim as new and wish to secure by Letters Patent is:

1. A boat comprising a buoyant member provided with a central opening, a bottom member attached to said buoyant member, said bottom member having restricted water passage openings therein, and a flexible water-proof load inclosure member placed across the upper surface of the buoyant member and depressed into the opening in the buoyant member so that a portion of said flexible member rests against the bottom and is below the level of the water admitted by said restricted water passage openings.

2. A boat comprising a buoyant member provided with a central opening, a boat bottom attached to the buoyant member and having restricted openings therein, and a flexible member placed across the upper surface of the buoyant member and adapted to overlie said upper surface to produce an air seal between this surface and the flexible member, said flexible member being depressed into the opening in the buoyant member to form a load inclosure and to complete a trapped water space bounded by the flexible member, the buoyant member and the boat bottom, said restricted openings in the boat bottom affording a controlled liquid flow to and from the trapped water space.

3. A boat comprising a buoyant member provided with a central opening, a boat bottom attached to the underside of the buoyant member, a flexible waterproof sheet placed across the upper surface of the buoyant member and depressed into the opening in said member until it rests against the boat bottom, said flexible sheet providing a load inclosure and completing a trapped water space bounded by the flexible sheet, the buoyant member and the boat bottom, and a plurality of restricted openings in the boat bottom affording a controlled liquid flow to or from the trapped water space.

4. A knockdown boat comprising a plurality of inflatable buoyant elements, a substantially doughnut shaped housing for said elements, a boat bottom attached to a continuation of said housing, a flexible waterproof sheet placed across the upper surface of the housing for the inflatable buoyant elements and adapted to overlie said upper surface to produce an air seal between this surface and the flexible sheet, said flexible sheet being depressed into the opening in the housing for the buoyant elements to form a load inclosure and to complete a space bounded by the flexible sheet, the housing for the buoyant elements and the boat bottom, and a plurality of restricted openings in the boat bottom which permit liquid to enter said space to act as a stabilizing means for the boat.

5. A knockdown inflatable boat comprising a plurality of inflatable elements individually housed in a multicompartment housing of substantially doughnut shape, a boat bottom attached to a continuation of said housing, a flexible member placed across the upper surface of said housing and overlying said housing to form a loose air seal between the housing and the flexible member, said flexible member being depressed into the opening in said substantially doughnut-shaped housing to form a load inclosure and to complete a space bounded by the flexible member, the multicompartment housing, and the boat bottom, and means for stabilizing the boat, said means including water trapped in the space bounded by the flexible member, the multicompartment housing, and the boat bottom.

6. A pneumatic boat comprising a plurality of inflatable elements, a substantially doughnut-shaped housing for the inflatable elements, a boat bottom attached to said housing, a waterproof sheet placed across the upper surface of said housing to form a loose air seal between this surface and the sheet, said sheet being depressed into the opening in the substantially doughnut-shaped housing until the sheet rests against the upper surface of the boat bottom and completes a space bounded by the sheet, the boat bottom, and the inflatable element housing, and a plurality of restricted ports in the boat bottom which allow liquid to slowly enter or leave said space, whereby the boat is stabilized by the weight of liquid trapped in said space and by a force opposing the force exerted by the air trapped above the water in said space.

7. In a boat, a bottom comprising a substantially flat bottom member, and a plurality of strips attached to a surface of said member to form tubes, reinforcing members removably mounted in said tubes, at least one of said strips being placed at an angle to the others and means for securing said reinforcing members in place in said strips.

8. In a boat, a substantially flat bottom, a plurality of strips attached to said bottom to form tubes, readily removable bottom reinforcing members in said tubes, a flange attached to said bottom and having openings therein, said openings in said flange adapted to receive the bottom reinforcing members and means mounted on said flange for securing said reinforcing members in place in said strips.

9. A boat including a plurality of inflatable elements individually housed in a multi-compartment housing of substantially doughnut shape, said individual compartments being of approximately equal size and symmetrically disposed about the center of the boat, and said housing

having depending substantially vertical extensions therefrom, a substantially vertical flange member supported between said extensions, and a boat bottom attached to said flange member.

10. In an inflatable boat, an inflatable member forming a part of the boat and having an inflation and deflation opening, a housing for said inflatable member, said housing having an opening therein in alignment with the opening in the inflatable member, a plurality of tabs adjacent the opening in said housing, a wide aperture low pressure valve extending through both the opening in the inflatable member and the opening in the housing therefor, said valve comprising a body member having a liquid filled valve stop mounted therein, and a plurality of resilient members engaging the tabs adjacent the opening in the housing for the inflatable member and surrounding said valve to hold it in position.

11. In a boat, an inflatable member forming a part of the boat and having an opening therein, a bottle-neck shaped wide-aperture low-pressure valve member located in said opening, said valve member engaging the sides of the opening in said inflatable member to cause the portions of the inflatable member adjacent said opening to conform to the shape of the exterior of said valve member, said valve member having a liquid-filled valve stop mounted therein, a plurality of tabs located adjacent the opening in said inflatable member and a plurality of resilient members engaging said tabs and said valve member to hold the latter in position.

12. In a boat, an inflatable member forming a part of the boat and having an opening therein, a housing for said inflatable member, said housing having an opening therein in alignment with the opening in the inflatable member, a plurality of tabs adjacent the opening in said housing, a

valve extending through both openings, said valve comprising a body member having a low freezing point liquid-filled valve stop mounted therein, and a plurality of resilient members engaging the tabs adjacent the opening in the housing for the inflatable member and also engaging the valve member to hold the latter in position.

13. In an inflatable boat, a plurality of buoyant elements and a housing therefor, an extension formed on said housing and having openings therein, a substantially flat bottom attached to said extension and reinforcing members removably mounted on said bottom, said reinforcing members adapted to extend through the openings in said extension.

14. In an inflatable boat, a plurality of pneumatic supporting members, individual housings for the pneumatic supporting members, a single annular flange attached to said housings and having openings therein, said flange forming a continuation of the undersides of the individual housings, a substantially flat bottom attached to said flange and reinforcing members removably mounted on said bottom, said reinforcing members adapted to extend through the openings in said flange.

15. In an inflatable boat, a plurality of pneumatic supporting members and a housing therefor, an extension formed on said housing and having restricted openings therein, a substantially flat bottom attached to said extension and having restricted openings therein and reinforcing members removably mounted on said bottom, said reinforcing members adapted to extend through the openings in said flange and said restricted openings affording a controlled water flow through said bottom.

CRESSON H. KEARNY.
